UNITED STATES PATENT OFFICE

136,091

DESIGN FOR AN ISOMETRIC DRAFTER

Alphonso Edwin Tripp, Detroit, Mich.

Application May 21, 1943, Serial No. 110,252

Term of patent 7 years

To all whom it may concern:

Be it known that I, Alphonso Edwin Tripp, a citizen of the United States, residing at Detroit, in the county of Wayne and State of Michigan, have invented a new, original, and ornamental Design for an Isometric Drafter, of which the following is a specification, reference being had to the accompanying drawing, forming part thereof.

Figure 1 is a top plan view of an isometric drafter showing my new design.

Figure 2 is a side elevational view, and
Figure 3 is an edge view thereof.

I claim:

The ornamental design for an isometric drafter, as shown.

ALPHONSO EDWIN TRIPP.
